UNITED STATES PATENT OFFICE.

HENRY BOOT, OF PHILADELPHIA, PENNSYLVANIA, ASSIGNOR TO THOMAS DOLAN, OF SAME PLACE.

DESIGN FOR A SHAWL-PATTERN.

Specification forming part of Design No. 5,479, dated January 23, 1872.

Specification describing a Design for a Shawl-Pattern, produced or invented by HENRY BOOT, of Philadelphia, Pennsylvania.

The main characteristic of my design is illustrated by the diagram, Fig. 2, Figure 1 showing the application of this main feature to a strip of shawl-fabric, in which stripes A and B are bounded by a peculiar edging, best observed in Fig. 1. This edging consists of a series of pointed projections, *a a*, united at their bases with inclined lines *b b*.

It is immaterial, in carrying out my design, how wide or how numerous the stripes of the pattern may be, or how they are disposed of as

regards position or color; but it is essential that the shawl-pattern should consist of a series of stripes, and that these stripes should be bounded by the peculiar denticulated edging.

I claim as my invention—

A design for a shawl-pattern, in which is a series of stripes bounded by the denticulated edging, illustrated and described.

In testimony whereof I have signed my name to this specification in the presence of two subscribing witnesses.

Witnesses: HENRY BOOT.
